US0D1044793S

(12) **United States Design Patent** (10) **Patent No.:** **US D1,044,793 S**
(45) **Date of Patent:** **** Oct. 1, 2024**

(54) **ALL-IN-ONE COMPUTER**

(71) Applicant: **Lenovo (Beijing) Co., Ltd.**, Beijing (CN)

(72) Inventor: **Xi Chen**, Beijing (CN)

(73) Assignee: **Lenovo (Beijing) Co., Ltd.**, Beijing (CN)

(**) Term: **15 Years**

(21) Appl. No.: **29/790,221**

(22) Filed: **Nov. 11, 2021**

Related U.S. Application Data

(62) Division of application No. 35/509,641, filed on Sep. 29, 2019 (U.S. filing date under 35 U.S.C. 384), and having an international filing date of Sep. 29, 2019, now Pat. No. Des. 938,412.

(57) **CLAIM**

The ornamental design for an all-in-one computer, as shown and described.

DESCRIPTION

FIG. 1 is a front view of an all-in-one computer showing the new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a front, right side perspective view thereof;

FIG. 8 is a front, right side perspective view thereof showing the camera closed; and,

FIG. 9 is a back view thereof showing the camera closed. The broken lines shown in the drawings illustrate portions of the all-in-one computer that form no part of the claimed design.

1 Claim, 9 Drawing Sheets
